DOORCHECK FOR RAILROAD CARS

Filed Nov. 6, 1929

UNITED STATES PATENT OFFICE

MILTON P. McLAUGHLIN, OF WAKEFIELD, MASSACHUSETTS

DOORCHECK FOR RAILROAD CARS

Application filed November 6, 1929. Serial No. 405,153.

The invention relates to a check adapted to so retard the closing movement of a hinged railroad car door, as to prevent liability of injury to the hand of a passenger who may 5 be standing in the doorway just before the car stops, the hand resting on the door casing in such position that it is liable to be pinched when the wheel brakes are applied and the inertia of the door causes it to abruptly close. Accidents of this character frequently occur, and often involve serious injury to passengers, and expense to a railroad company resulting from claims for damage.

The object of the invention is to provide 15 a door check of simple and durable construction, adapted to stop the closing movement of said door before it is closed sufficiently to pinch a hand in its path, and thereafter offer a minimum resistance, so that the door may 20 be readily pushed to its closed and latched position, and to exert balanced upward and downward pressure on the door for a purpose hereinafter stated.

Of the accompanying drawings forming a 25 part of this specification—

Figure 1 shows in perspective a door casing, a door hinged thereto, and a check embodying the invention, the door being ajar.

Figure 2 is a section on line 2—2 of Figure 30 1, showing the check elements separated from each other.

Figure 3 is a sectional view, showing the check elements as they appear at the commencement of the checking operation.

Figure 4 is a sectional view, showing the 35 checking elements as they appear when the door is fully closed.

Figure 5 is a view similar to a portion of Figure 4, showing the flexing means herein- 40 after described, in a position intermediate the positions shown by Figures 3 and 4.

The same reference characters indicate the same parts in all of the figures.

In the drawings 10 designates a door casing, and 11 a door hinged thereto.

My improved check is composed of two co-operating elements or members, one attachable to the casing, and the other to the door, each member having attaching means locat- 50 ing it above the path in which the door moves,

One member includes a pair of spring brake members 130, one above the other supported in inclined positions relative to the path of the door. The other element includes an unyieldingly supported flexing member 140, 55 formed and arranged to contact with the brake members 130 when the door is moving toward and to its closed position, so that the brake members and the flexing member co-operate in retarding the closing movement of 60 the door, and stopping it before its swinging edge reaches a position causing it to pinch a hand resting on the upright member of the casing against which the door closes.

Each brake member 130 is an elongated 65 spring of phosphor bronze or other suitable material, two leaves or layers being preferably employed. One end of each brake member is fixed to a holder comprising an attaching base 150, and an arm 160, projecting from the base, the outer end of the arm being provided with inclined seats 210, to which the outer ends of the brake members are attached, preferably by rivets 170. The brake members are thus positioned so that they are oppositely inclined and diverge from the arm 16, as shown, one brake member being inclined inwardly and upwardly, and the other inwardly and downwardly, from its fixed end.

The flexing member 140 is, in this instance, 75 a bracket 190, which includes an attaching base 180, and an arm projecting above the door and having a slot 200, the upper and lower walls of which constitute upper and lower deflectors 140. The arrangement is such that when the door is closing, the slot receives the outer end portions of the arm 160 and brake members 130, while the door is considerably ajar, as shown by Figure 1, the outer portions of the brake members bearing on the deflectors 140. Movement of the door toward its closed position causes the deflectors to inwardly flex the brakes.

The brake members have elongated free 85 end portions not backed by the seats 210, and so inclined that they are pressed inward by the deflecting faces when the door moves from the position shown by Figure 1, toward its closed position. The resistance to the closing movement of the door caused by the 90 100

contact of the brake members with the deflectors, increases during the initial movement of the door from the position shown by Figure 3, until the deflectors reach approximately the mid-length of the free end portions of the brake members.

The force of the springs constituting the brake members 130, is so proportioned to the momentum of the door that the said resistance stops the closing movement before the door reaches a pinching position relative to an upright member of the casing, and renders the door incapable of pinching a hand in the path of its swinging edge.

Thereafter and during the completion of the closing movement, the resistance decreases as the deflectors 140 approach the free ends of the brake members, so that the final closing of the door may be easily caused by pushing the door to its closed position.

When the door is closing, the slot 200 receives the outer end portions of the arm 160 and brake members 130, while the door is considerably ajar, as shown by Figure 3. Further movement of the door toward its closed position causes the deflectors 140 to flex the brake members 130 toward each other. The elongated free end portions of the brake members, normally inclined, as shown by Figures 2 and 3, increasingly resist the closing movement of the door until the deflectors move inwardly approximately to the midlength of said free end portions, as shown by Figure 5. The increasing resistance stops the closing movement of the door before it is closed to a pinching position, and when the deflectors are in approximately the position shown by Figure 5. Thereafter the resistance to the closing movement decreases as the deflecting faces approach the free ends of the brake members, so that the door may be easily pushed to its closed position shown by Figure 4.

When the closed door is unlatched, the outward pressure, exerted by the free end portions of the brake members on the deflectors, has a tendency to start the opening movement of the door, the brake members being longitudinally curved, as shown by Figures 2 and 3, to increase said tendency.

The base 150 may be attached by screws or bolts to the casing, and the base 180 may be similarly attached to the door.

Because of the fact that there are two deflectors 140, one facing upward and the other downward, and two brake members 130, one facing upward, and the other downward, one brake exerts an upward pressure on the door, and the other a downward pressure, through the flexing member 190. The two pressures are balanced, one neutralizing the other, so that the door hinges are not caused by the retarding and stopping means to bind on each other. If the retarding means included only one brake member and one deflector, said

means would exert a pressure on the door on one direction only, and would cause the hinges to so bind on each other as to prevent a desirably free working of the hinges.

I claim:

For use with a door casing and a door connected therewith by vertical hinges, a balancing door check adapted to stop the closing movement of the door before its swinging edge reaches a pinching position relative to an upright member of the casing, said check comprising a brake member including a holder adapted to be attached to the top member of the casing and projecting therefrom above the path of the door, and a pair of elongated spring brake members fixed at their outer ends to the holder, one brake member having a free portion inclined upwardly and inwardly from the outer end of the holder, while the other brake member has a free portion inclined downwardly and inwardly from said outer end, and a brake deflecting member adapted to be attached to the upper end of the door and projecting above the path thereof, and provided in its projecting portion with a pair of spaced apart deflectors arranged to slide upon and oppositely deflect said brake members simultaneously, and stop the movement of the door before it reaches a pinching position, the arrangement being such that the pressure exerted by the brake members on the deflectors is balanced, to prevent binding of the door hinges on each other.

In testimony whereof I have affixed my signature.

MILTON P. McLAUGHLIN.
